UNITED STATES PATENT OFFICE.

JOHN ANDLEY GRANT, OF ATLANTA, GEORGIA.

ATTACHMENT FOR FORD AUTOMOBILES.

1,411,623.

Specification of Letters Patent.

Patented Apr. 4, 1922.

Application filed November 14, 1921. Serial No. 514,947.

To all whom it may concern:

Be it known that I, JOHN A. GRANT, a citizen of the United States, residing at Atlanta, in the county of Fulton, State of

5 Georgia, have invented certain new and useful Improvements in Attachments for Ford Automobiles, of which the following is a description, reference being had to the accompanying drawing and to the figures of reference marked thereon.

10 This invention relates to attachments for Ford automobiles, and more particularly to an attachment to the oil draining pet-cock on the crank case.

15 The principal object of this invention resides in providing such an attachment whereby the pet-cock may be operated from the running board, or other convenient point, so that it is not necessary to reach under 20 the car and turn the cock, as heretofore.

A further object of this invention resides in providing a simple attachment of the character described, which can be quickly attached to the Ford with the minimum expense.

25 Still another object of this invention is to provide an attachment of the above character constructed and arranged so that it will not rattle when the car is traveling and 30 will always be in position to be instantly operated.

These and other objects will be obvious from a perusal of the specification taken in 35 connection with the accompanying drawings, in which—

Figure 1 is a view partly in section, showing the relation of the pet-cock, the running board and the attachment therefor;

40 Figure 2 is an enlarged detailed view of the pet-cock and inner end of the reach rod; and

Figure 3 is an enlarged detailed view of the handle end of the reach rod.

Referring now to the drawings in detail, 45 the crank case of a Ford automobile is indicated by the numeral 1. It is provided with the usual oil draining pet cock 2, which may be turned to permit the efflux of oil 50 in the crank case to the ground under the car. By this means the operator can ascertain the amount of oil in the case. The side frame of the machine is indicated at 3; the running board at 4 and the running board shield at 5. All the foregoing is of the usual 55 Ford construction.

At present it is the practice to reach under the car and manually turn the pet cock when it is desired to ascertain the condition of the oil supply in the crank case.

The present attachment provides a very 60 simple and facile device for permitting the operation of this pet cock from any convenient point on the exterior portion of the car. In the present instance the running board shield 5 is provided with an aperture 6, 65 through which extends a reach or turn rod 7, the inner end of which is provided with a bend or bow 8, adapted to pass through a perforation 9 in the finger piece 10 of the pet cock. A cotter pin 11 is preferably used 70 to prevent disconnection of these parts. The outer end of the reach rod 7 passes through the opening 6 in the shield 5, and is provided with a laterally bent handle portion 12, substantially of the form as indicated in the 75 drawing. The free end of the rod 13 is bent backwardly on itself and passes through the opening 5, as clearly shown in Fig. 3. By means of this construction there is provided a handle having resilient arms or portions 80 which, due to their springiness, grip the interior walls of the aperture 6 and prevent the rod from rattling when the automobile is in operation. It will also be observed that this construction does not interfere with the 85 instant operation of the reach rod which will always remain in its turned position. While the reach rod may be otherwise constructed and may be extended to or through other portions of the housing of the car, and 90 while it is obvious that there are other modes of connecting the inner end of the reach rod with the pet-cock, it is thought that the present embodiment presents the most 95 advantageous features of such various modifications of the invention which fall within the scope of the appended claims.

Having thus described my invention, what I claim as new and desire to secure by Letters Patent of the United States, is:

100 1. In combination with the oil drain pet cock of a crank case and the running-board-shield, a turn rod having its inner end connected to said pet cock and its outer end passing through an aperture in said shield, 105 the outer end of the rod having a portion bent to form a handle and a portion bent backwardly on itself to form a finger re-entering said aperture in the shield, whereby the natural resiliency of said re-entrant por- 110

tion presses said rod and said re-entrant portion into contact with the wall of said opening to keep said rod from rattling.

2. In combination with the oil drain pet cock of a Ford crank case, a turn rod having its inner end connected to said pet cock and its outer end extending outwardly from under and passing through an aperture in a portion of the car, so that it may be operated without reaching under the car, the

outer end of the rod having a portion bent to form a handle and a portion bent backwardly on itself to form a finger re-entering said aperture, whereby the natural resiliency of said re-entrant portion presses said rod and said re-entrant portion into contact with the wall of said aperture to keep said rod in firm position.

In testimony whereof, I affix my signature.

JOHN ANDLEY GRANT.
